UNITED STATES PATENT OFFICE.

WILLIAM H. STINE, OF MARIETTA, INDIANA.

TENSION FOR SELF-BINDERS.

SPECIFICATION forming part of Letters Patent No. 379,083, dated March 6, 1888.

Application filed July 21, 1887. Serial No. 244,928. (No model.)

To all whom it may concern:

Be it known that I, WILLIAM H. STINE, a resident of Marietta, in the county of Shelby and State of Indiana, have invented certain new and useful Improvements in Tension Devices for Grain Automatical Twine-Binders, of which the following is a specification.

My improvement relates to tension devices for grain automatical twine-binders in which 10 friction-rollers operate conjointly, and the object of my improvement is to prevent the frequent breaking and irregular tension of uneven or knotted twine in the process of binding. I attain this object by the mechanism illustrated 15 in the following drawings.

Figure 1 is a side view of the device in a horizontal position; Fig. 2, a top view, and Fig. 3 a top view with the upper part of the arm and rollers removed.

Similar letters refer to similar parts throughout the several views.

The rollers $r r'$ rotate on their axles or pins $P P'$, which pass through and are firmly held by the upward projections of their respective 25 holders $h h'$, arranged in line on the base b , with the rollers parallel and approximate. The holder h' is stationary. The holder h is provided with a slot, sl , allowing it to slide lengthwise under the head of the screw sc' in 30 the base b . The arms of the yoke y include the roller r and are secured to the holder h , its extension ex passing through the eye of the vertical arm of the holder h' , upon which is placed the spring sp . The angular arm a is 35 fastened to the box b' , or to an extension of the base b , its eye e resting over the line of contact between the rollers.

The tension device may be confined to the box b' or used separately, to suit the construction of the binder. The box b' may be of any

convenient shape or size. In Fig. 1 parts of its front are cut away to show the twine ball tb and the lower end of the screw sc . The thread t passes from the ball through the eye e' of the base b , between the rollers, through 45 the eye e of the arm a , and thence through the usual guides to the needle of the binder. The spring sp' separates the rollers when the spring sp is relaxed. By compressing the spring sp with the nut n the roller r' is drawn to the 50 roller r , pressing the thread between them with the force required to secure the proper tension, the springs affording sufficient elasticity to allow enlargements or knots of the thread to pass without unnecessary straining. 55

This device may be used in any required position, and may be applied to any twine-binder now in use.

What I claim, and desire to secure by Letters Patent of the United States, is—

The combination, in a tension device, of the twine-box b' , the eye e' in the base b , the base b , the holder h , with its slot sl , the set-screw sc' in the base b and through the slot sl , the arm a , its lower end fastened to the top of the 65 box b' and its upper end projecting over the roller r , holder h' , with its vertical arms to form bearings for the journals of the roller r' , and its vertical extension to form a bearing for the extension of the yoke y , the rollers $r r'$, 70 the journals $P P'$, the yoke y , secured at one end to the holder h and having at the other end an extension, ex , the nut n , the springs $sp sp'$, and the eye e in the upper end of the arm a , all substantially as above described, 75 and for the purpose set forth.

WILLIAM H. STINE.
